R. E. T. RHAMES

APPARATUS FOR ADMINISTERING ANÆSTHETICS

Filed March 22, 1923

Fig. 1

Inventor:

Rudolph E. J. Phamell,
by his attorney,
Charles T. Gooding.

UNITED STATES PATENT OFFICE.

RUDOLPH E. T. RHAMES, OF BOSTON, MASSACHUSETTS.

APPARATUS FOR ADMINISTERING ANÆSTHETICS.

Application filed March 22, 1923. Serial No. 626,941.

To all whom it may concern:

Be it known that I, RUDOLPH E. T. RHAMES, a subject of King George V, of Great Britain, residing at Boston, in the county of Suffolk and State of Massachusetts, have invented new and useful Improvements in Apparatus for Administering Anæsthetics, of which the following is a specification.

10 This invention relates to an improved apparatus for administering anæsthetics and has for its object to provide a simple, efficient apparatus through the medium of which liquid anæsthetics such as ether and

15 chloroform may be vaporized and administered by physicians to patients.

Another object of the invention is to provide an apparatus in which a liquid anæsthetic may be fed, either by gravity or under pressure, from a container in which it is stored to a hood secured beneath said container, said hood resting upon the face of the patient, the anæsthetic being supplied either in drops or in a spray to an absorbent material from which the fumes are inhaled by the patient.

Another object of the invention is to provide a means for indicating the rate of feed of the liquid anæsthetic from the container to the hood.

Still another object of the invention is to provide an apparatus which may be utilized in administering gaseous anæsthetics and oxygen gas which are not stored in the container of the apparatus, but are stored in separate containers and are delivered to the hood of the apparatus of this invention by any suitable conducting means which may be connected to the hood.

40 The invention consists in the combination and arrangement of parts set forth in the following specification and particularly pointed out in the claims thereof.

Referring to the drawings:

45 Figure 1 represents a central vertical section through an apparatus embodying the invention.

Fig. 2 is a plan view of the upper portion of the apparatus.

50 Fig. 3 is a detail section taken on the line 3—3 of Fig. 2.

Fig. 4 is a detail elevation illustrating the mechanism that permits the hood to be adjusted relatively to the base.

Like numerals refer to like parts throughout the several views of the drawings.

In the drawings, 5 represents a container for a liquid anæsthetic, as for example, ether or chloroform, said container comprising a base 6, a transparent cylindrical member 7 mounted upon said base and a cap 8 in which a filling opening 9 is provided through which the anæsthetic is supplied to the interior of the container. The filling opening 9 is provided with a suitable cover 10. Formed integral with the base 6 and also concentrically disposed relatively thereto is a pressure cylinder 11 from the upper end of which projects a tubular extension 12 which is screw-threaded at its upper end to receive a nut 13, the latter being provided to clamp the base 6, transparent member 7 and cap 8 tightly together. A gasket 14 is interposed between the base 6 and the lower edge of the transparent member 7, while another gasket 15 is similarly interposed between the cap 8 and upper edge of said transparent member.

Located within the pressure cylinder 11 is a piston 16 provided with a tubular piston rod 17 which extends upwardly through the tubular extension 12 and said piston rod has a handle 18 fastened at the upper end thereof through the medium of which a reciprocatory motion may be imparted to said piston. The piston 16 is prevented from rotating within the cylinder 11 by a pin 19 which projects from the upper portion of the cylinder 11 into a groove 20 provided in the tubular piston rod 17. Ports 21 are provided in the side wall of the pressure cylinder 11 and form a means whereby the liquid anæsthetic may pass from the interior of the container 5 to the interior of the pressure cylinder 11. Small bleed openings 22 are also provided extending through the upper end of the pressure cylinder and said openings also connect the interior of the container 5 with the interior of the pressure cylinder 11.

Located at the lower end of the pressure cylinder 11 and constituting a part thereof is a detachable end member 23 in which a discharge port 24 is provided together with other ports 25 which connect the interior of the pressure cylinder with said dis-

charge port 24. The discharge port 24 has a needle valve 26 provided therefor having a valve rod 27 which has screw-threaded engagement at 28 with the member 23 and said valve rod extends upwardly through the tubular piston rod 17 and has a knob 29 rigidly fastened at its upper end.

An indicator 30 is fastened to the valve rod 27 by a screw 31 and said indicator registers with graduations 32 provided upon the upper surface of a circular portion 33 of the handle 18, and indicates the extent to which the valve 26 has been raised from the discharge port 24, together with the rate of feed of the liquid anæsthetic through said discharge port in drops per minute. The screw thread 28 is preferably a double thread in order that one rotation of the valve rod 27 will entirely open or close the discharge port 24. A spring 34 is interposed between the end member 23 and the piston 16 and said spring always acts to force said piston upwardly and hold the same in its normal position, as illustrated in Fig. 1.

Detachably secured at the lower end of the pressure cylinder 11 beneath the end member 23 thereof is a spray nozzle 35 provided with a plurality of small openings 351 formed therein through which the liquid may either drip or be forced in a spray, as desired. When in position, as illustrated in Figure 1, the nozzle 35 abuts against the end surface of the member 23 and thereby acts as a check nut to prevent the end member 23 from rotating and thereby becoming loosened within the body portion of the pressure cylinder. It is evident that the liquid anæsthetic when allowed to flow through the discharge port 24 may drip slowly through one or more of the openings 351, as desired, and as regulated by the position of the valve 26, or pressure may be applied upon the anæsthetic within the pressure cylinder 11 by operating the piston 16 upon which occasion a spray will be formed by the nozzle 35.

Extending downwardly from the main portion of the base 6 is an annular flange 36 in which a plurality of openings 37 are provided. Detachably secured to the flange 36 through the medium of a plurality of screws 38 is a hood 39 which is of suitable size and form to cover the face of a person, around the latter's nose and mouth. The hood 39 is provided with slots 40 through which the screws 38 project thereby allowing said hood 39 to be rotated slightly upon the base 6, and openings 41 are formed in the hood 39 aligning with the openings 37 of the flange 36 and the amount of air admitted within the hood 39 may be regulated by rotating said hood upon said flange and moving the openings 41 relatively to the openings 37 thereby increasing or decreasing the size of the actual opening into the hood.

A cup-shaped screen 42, preferably formed of fine mesh wire, is located in an inverted position within the hood 39 and a layer of suitable absorbent material 43 covers the upper surface of said screen. A pneumatic cushion 44 is held against the lower edge of the hood 39, said cushion being provided with a flap 45 which is stretched around the periphery of said hood above a bead 46 located at the lower edge of said hood. The cushion 44 is provided with a tube 47 through which air is blown into said cushion, after which said tube is closed through the medium of a suitable clamp 48 which pinches the sides of the tube together and thereby holds the air within the cushion. A nipple 49 is secured to the hood 39, said nipple having a passage extending therethrough which is normally closed through the medium of a thumb screw 50 and when it is desired to administer gaseous anæsthetics or oxygen gas which are held in separate containers, the same is accomplished by attaching a suitable conductor leading from said containers to said nipple.

In its operation, the apparatus is placed upon the face of the patient and the rate of feed of the anæsthetic from the container 5 through the pressure cylinder 11 to the absorbent material 43 within the hood 39 is regulated by rotating the knob 29 in the proper direction to lift the valve 26 from its seat at the discharge port 24, said knob 29 being rotated until the indicator 30 aligns with a graduation 32 which designates the number 90 of drops per minute that it is desired to feed to the absorbent material. When the anæsthetic is fed by gravity alone, the spray nozzle 35 may or may not be used as desired. If the nozzle is not used, the anæsthetic will drop directly through the discharge port 24 upon the absorbent material 43. When the spray nozzle 35 is used, the anæsthetic will drop through the discharge port 24 upon said nozzle, and drip through one or more of the openings 351, the number of said openings through which said anæsthetic will drop being determined by the position of the valve 26. When a spray is desired, the piston 16 is forced downwardly within the pressure cylinder 11 through the medium of the piston rod 17 and handle 18 and the anæsthetic is forced through the discharge port 24 and openings 351 in the spray nozzle 35. The spring 34 always acts to force the piston 16 upwardly into its normal position and in its upward movement as said piston approaches the upper portion of the pressure cylinder the liquid within said cylinder above said piston will pass from said cylinder through the bleed openings 22 into the container. The amount of air which is admitted to the interior of the hood 39 is regulated by rotating said hood upon the flange 36 of the base 6 and thereby moving the openings 41 in the 95 100 105 110 115 120 125 130

hood relatively to the openings 37 in the flange 36.

Upon occasions when it is desired to utilize the apparatus to administer gaseous anæsthetics or oxygen gas to patients, a conductor from the container in which said anæsthetics or gas are contained is secured to the nipple 49 fast in the hood 39 and the patient inhales these gases in exactly the same manner as the vapor of the liquid anæsthetics previously mentioned.

I claim:

1. An apparatus for administering anæsthetics comprising, in combination, a hood, a container for an anæsthetic mounted upon said hood, a pressure cylinder for said anæsthetic interposed between said hood and said container and communicating with both and means to force said anæsthetic from said pressure cylinder into said hood.

2. An apparatus for administering anæsthetics comprising, in combination, a hood, a container for an anæsthetic mounted upon said hood, a pressure cylinder for said anæsthetic interposed between said hood and said container and communicating with both, means to force said anæsthetic from said pressure cylinder into said hood and means to produce a spray of said anæsthetic as it passes from said pressure cylinder into said hood.

3. An apparatus for administering anæsthetics comprising, in combination, a hood, a container for an anæsthetic mounted upon said hood, a pressure cylinder for said anæsthetic interposed between said hood and said container and communicating with both, means to force said anæsthetic from said pressure cylinder into said hood and means to regulate the amount of said anæsthetic passing to said hood.

4. An apparatus for administering anæsthetics comprising, in combination, a hood, a container for an anæsthetic mounted upon said hood, a pressure cylinder for said anæsthetic communicating with said container and provided with a discharge port communicating with said hood, means to force said anæsthetic from said pressure cylinder through said discharge port into said hood and a valve to regulate the amount of said anæsthetic passing through said discharge port.

5. An apparatus for administering anæsthetics comprising, in combination, a hood, a container for an anæsthetic mounted upon said hood, a pressure cylinder for said anæsthetic located within said container, the interior of said cylinder communicating with the interior of said container, said cylinder also being provided with a discharge port communicating with said hood, means to force said anæsthetic from said pressure cylinder through said discharge

port into said hood and means to regulate the amount of said anæsthetic passing through said discharge port.

6. An apparatus for administering anæsthetics comprising, in combination, a hood, a container for an anæsthetic mounted upon said hood, a pressure cylinder for said anæsthetic located within said container, the interior of said cylinder communicating with the interior of said container, said cylinder also being provided with a discharge port communicating with said hood, means to force said anæsthetic from said pressure cylinder through said discharge port, means to produce a spray of said anæsthetic and means to regulate the amount of said anæsthetic passing through said discharge port.

7. An apparatus for administering anæsthetics comprising, in combination, a hood, a container for an anæsthetic mounted upon said hood, a pressure cylinder for said anæsthetic located within said container, the interior of said cylinder communicating with the interior of said container, said cylinder also being provided with a discharge port communicating with said hood, means to force said anæsthetic from said pressure cylinder through said discharge port, means to produce a spray of said anæsthetic, means to regulate the amount of said anæsthetic passing through said discharge port and means to indicate the rate of feed of said anæsthetic.

8. An apparatus for administering anæsthetics comprising, in combination, a hood, a container for an anæsthetic mounted upon said hood, a pressure cylinder for said anæsthetic located within said container, the interior of said cylinder communicating with the interior of said container, said cylinder also being provided with a discharge port communicating with said hood, a piston to force said anæsthetic from said pressure cylinder through said discharge port into said hood and a valve to regulate the amount of said anæsthetic passing through said discharge port.

9. An apparatus for administering anæsthetics comprising, in combination, a hood, a container for an anæsthetic mounted upon said hood, a pressure cylinder for said anæsthetic located within said container, the interior of said cylinder communicating with the interior of said container, said cylinder also being provided with a discharge port communicating with said hood, a piston to force said anæsthetic from said pressure cylinder through said discharge port, a spray nozzle fast to said pressure cylinder beneath said discharge port and a valve to regulate the amount of said anæsthetic passing through said discharge port.

10. An apparatus for administering an-

æsthetics comprising, in combination, a hood, a container for an anæsthetic mounted upon said hood, a pressure cylinder for said anæsthetic located within said container, the 5 interior of said cylinder communicating with the interior of said container, said cylinder also being provided with a discharge port communicating with said hood, a piston to force said anæsthetic from said pressure cylinder through said discharge port, a spray nozzle fast to said pressure cylinder beneath said discharge port, a valve to regulate the amount of said anæsthetic passing through said discharge port and means to indicate the rate of feed of said anæsthetic.

10 11. An apparatus for administering anæsthetics comprising, in combination, a hood, a container for an anæsthetic mounted upon said hood, a pressure cylinder for said anæsthetic located within said container, the 20 interior of said cylinder communicating with the interior of said container, said cylinder also being provided with a discharge port communicating with said hood, a piston to force said anæsthetic from said pressure cylinder through said discharge port, means to return said piston to its normal position, a spray nozzle fast to said pressure cylinder beneath said discharge port, a valve for said discharge port, and means to indicate the rate of feed of said anæsthetic.

15 12. An apparatus for administering anæsthetics comprising, in combination, a hood, a container for an anæsthetic mounted upon said hood, a pressure cylinder for said anæsthetic located within said container, the 30 interior of said cylinder communicating with the interior of said container, said cylinder also being provided with a discharge port communicating with said hood, a piston within said cylinder, a tubular piston rod extending upwardly through said container, a handle for said piston rod, a spray nozzle fast to said pressure cylinder beneath said discharge port, a valve for said discharge port, a valve rod extending through said piston rod and a handle fast to said valve rod.

13. An apparatus for administering anæsthetics comprising, in combination, a hood, a container for an anæsthetic mounted upon said hood, a pressure cylinder for said anæsthetic located within said container, the 40 interior of said cylinder communicating with the interior of said container, said cylinder also being provided with a discharge port communicating with said hood, a piston within said cylinder, a tubular piston rod extending upwardly through said container, a handle for said piston rod, said

5 handle being provided with graduations thereon, a spray nozzle fast to said pressure cylinder beneath said discharge port, a valve for said discharge port, a valve rod extending through said piston rod, a handle fast to said valve rod and an indicator fast to said valve rod and registering with said graduations.

14. An apparatus for administering anæsthetics comprising, in combination, a hood 70 provided with openings therein, a container for an anæsthetic embodying therein a base mounted to rotate upon said hood and provided with an annular flange having openings therein normally aligning with the 75 openings in said hood, a pressure cylinder for said anæsthetic located within said container, the interior of said cylinder communicating with the interior of said container, said cylinder also being provided with a discharge port communicating with said hood, means to force said anæsthetic from said pressure cylinder through said discharge port into said hood and means to regulate the amount of said anæsthetic passing 80 through said discharge port.

15. An apparatus for administering anæsthetics comprising, in combination, a hood provided with openings therein, a container for an anæsthetic embodying therein a base mounted to rotate upon said hood and provided with an annular flange having openings therein normally aligning with the 90 openings in said hood, said container also embodying therein a transparent cylindrical member mounted upon said base and a cap; a pressure cylinder for said anæsthetic located within said container, the interior of 95 said cylinder communicating with the interior of said container, said cylinder being provided with a tubular extension projecting upwardly through said container, means fast to said tubular extension to clamp said base, cylindrical member and cap together, said cylinder also being provided with a discharge port communicating with said hood, a piston within said cylinder, a tubular piston rod extending upwardly through said tubular extension, a handle for said piston rod, a spray nozzle fast to said pressure cylinder beneath said discharge port and a 100 valve for said discharge port.

105 In testimony whereof I have hereunto set my hand in presence of two subscribing witnesses.
